UNITED STATES PATENT OFFICE.

DANIEL M. WINANS, OF BINGHAMTON, NEW YORK, ASSIGNOR TO THE BREWER-TITCHENER CORPORATION, OF CORTLAND, NEW YORK, A CORPORATION OF NEW YORK.

DETACHABLE LOCK FASTENER.

Application filed December 1, 1923. Serial No. 677,950.

To all whom it may concern:

Be it known that I, DANIEL M. WINANS, a citizen of the United States, and a resident of Binghamton and the county of Broome 5 and the State of New York, have invented certain new and useful Improvements in Detachable Lock Fasteners, of which the following is a specification.

My invention relates to a novel detachable 10 fastener for vehicle curtains, gloves, belts, brief cases and similar purposes, where it is desired to securely fasten and hold any two fabric flap sections together and yet be able quickly and conveniently to detach same 15 when so desired.

The object of this invention is to produce a neat and efficient fastener, more especially such as are adapted to be used in connection with motor-car or carriage curtains, and allow 20 of positively locking or unlocking such curtains to an undercut stud-post attached to either the body of the car or to another section of curtain fabric.

A further object is to provide an improved tongue and groove type of lock fastening device that will be simple and economical to manufacture and that will require a deliberate unlatching manipulation 25 before the curtain can be removed from the stud-post with which it may be engaged.

As regards the old style turn-button type of fastener, this usually employs light 30 springs for imparting a snap action to the button. After a prolonged period of service, such springs tend to rust or stick and otherwise become inoperative, and these 35 defects are found to seriously impair the usefulness of such devices.

In the case of the one-way snap fastener, 40 this type must usually be lifted in a certain definite direction of movement by manipulating curtain fabric to which the socket is attached. The considerable pull 45 that must be exerted upon the fabric to unsnap this type of curtain fastener and the resulting strain frequently leads to a cutting of the fabric around the washer or burr edges against which its socket element is clinched. Furthermore, such devices require 50 the use of considerable force in order to snap the socket back into place and this inherent stiffness of action usually necessitates a counter pressure to be exerted against the 55 opposite curtain carrying the stud-post member of such fasteners, all of which

mitigates against their utility for the purpose indicated.

The principle of operation underlying the present fastener differs from similar devices by embodying therein a number of novel and improved features of construction, new to this art that overcome defects in the older types and otherwise afford some important advantages.

The present invention provides for a combination of lock and snap fastener means that can readily be latched or unlatched at will by means of a control lever. When the latch is positively held out of engagement by said lever, the cap or female member of this fastener can be freely detached from its co-acting grooved stud or male member without having to overcome any snap action whatsoever. The control or actuating lever is provided with a convenient out-standing handle and there is therefore no need for taking hold of any portion of the curtain to manipulate this type of fastener.

Should it be desired to remount the fastener upon its stud-post, the removed 80 socket is again ready to freely enter the stud without any snap action, but the curtain may be subsequently locked into place by simply releasing the latching mechanism. If, on the other hand, it is desired 85 to release the latch prior to remounting the curtain upon its stud-post, my device is then capable of operating as a snap fastener per se, with the difference over previous devices that the curtain automatically becomes 90 positively locked after being snapped in place and cannot thereafter be removed from its stud-post until the actuating lever is again thrown into the proper position for disengaging the latch tongue from its locking groove.

Embodied herein are also other features of structure and organization designed to facilitate the manufacture of said fasteners and application of same to curtain fabrics, 100 all of which will be set forth in detail hereinafter.

Reference is had to the accompanying one sheet drawing which illustrates an example of the preferred form of my invention, like characters of reference indicate like parts in the several views, and in which drawing:

Fig. 1 is a detailed view in partial section of the assembled socket member of my 110

fastener showing the relation of parts prior to engaging the stud-post.

Fig. 2 is an elevational front view of Fig. 1, showing the dished cap parts of the socket member with the bail-shaped actuating lever placed in its mid-position.

Fig. 3 is an elevational rear view of Fig. 1, taken along the line 3-3.

Fig. 4 is a sectional view of the assembled 10 socket member as it appears when engaged with and locked to the stud-post, the actuating lever being thrown into its extreme lower position.

Fig. 5 is an elevational front view of Fig. 15 4, as taken in partial section along the line 5-5 to show the tongue and groove method of locking the socket member to the stud-post.

Fig. 6 is a side view of Fig. 5, and indicates the cam element whereby a lateral 20 movement is imparted to legs of the actuating lever for the purpose of engaging or disengaging the latching mechanism.

Fig. 7 represents the backing or clinch 25 plate which is mounted in the opposite side of the curtain fabric and engages the prongs on the dished cap of the socket member.

Fig. 8 represents the intermediate washer 30 plate which is mounted between the cap and the fabric and serves to re-enforce the latter, and also to hold the various parts in assembled relation.

Fig. 9 shows a plan view of the dished 35 cap provided with prongs and also journal recesses for fulcrumming the bail shaped actuating lever.

Fig. 10 is a sectional view of the cap showing the journal recess as taken along 40 the center line 10-10 of Fig. 9.

Fig. 11 is a sectional detail of the cap showing the cam elements as taken along the line 11-11 of Fig. 9.

Fig. 12 shows a detail of the resilient bail-shaped actuating lever of this fastener.

Fig. 13 indicates a modified stud-post attached to one fabric flap while the socket part is attached to an independent flap for the purpose of fastening such curtains together.

Fig. 14 shows an elongated stud-post upon which are mounted two distinct socket members, each fastened to separate curtain fabrics.

55 The constructive means whereby the indicated results are attained reside in part in the novel method of mounting a resilient bail-shaped actuating or control lever within the socket cap element of this device.

60 Referring first to Figs. 9 and 10, these show the dished-shaped or recessed socket cap, designated in its entirety as A, having a flat crown A₁ with raised cylindrically shaped side wall A₂. Formed integral with said side wall are a set of relatively long

prongs such as A₃, while the center of the crown A₁ is preferably perforated with a hole or aperture A₄. In addition, there are provided several shorter prongs such as A₇ which are oppositely disposed and used to assemble the cap, as will appear presently. The side wall A₂ is further provided with two aligned and oppositely disposed recessed slots or notches A₅ and A₆, which serve as bearings for mounting the aligned 75 fulcrum tongues of the control lever.

The last named lever designated in its entirety as B, is preferably made of suitably gauged spring wire and may be bent into a horse-shoe or bail-shaped contour as 80 is best shown in Fig. 12. This resilient bail type lever is provided with a loop portion or handle B₁ whose legs B₂ and B₃ are respectively bent to lie in a common plane and when mounted in place, said legs are intended 85 to be sprung apart somewhat into the position indicated in Fig. 5. Furthermore, each of the leg ends are sharply bent inwardly to form the aligned double fulcrum tongues B₄ and B₅ respectively, and these 90 are pointed toward each other to constitute a common fulcrum axis about which the lever is adapted to turn. The initial set given to the legs B₂ and B₃ causes them to 95 maintain a firm contact with respect to the adjacent side walls of the socket cap A when the fulcrum tongues B₄ and B₅ are mounted in their respective journal recesses A₅ and A₆.

It will also be seen that the ends of the tongues B₄ and B₅ are partially flattened off in the plane of the bail loop and these flattened faces serve as latch tongues which are made to engage or disengage with the undercut groove of the stud-post E of the male portion of this fastener, all of which will be more fully explained hereinafter.

As shown in Fig. 8, the intermediate washer plate C is provided with a central hole C₁ and also with a series of circumscribing perforations such as C₃ which register with the cap prongs A₃ and allow these to freely pass through the washer. The washer is further perforated with another set of holes such as C₂, adapted to register 115 with the shorter cap prongs A₇ which center the socket cap A with respect to the washer C. After the control lever B is properly mounted within the cap A as shown in Figs. 1 and 4, the washer C is pressed firmly 120 against the free circular edge of the cap side walls A₂ and the designated parts are held together by clinching said shorter prongs A₇ over the washer C to constitute an assembled socket unit.

The assembled socket is then mounted upon one side of the curtain fabric as is best shown in Figs. 1 and 2. The set of longer prongs such as A₃ are made to pierce the curtain fabric F and engage with the back- 130

ing plate D which is mounted on the opposite side of the fabric and clinched in the conventional manner indicated in Fig. 3. The fabric is also pierced with a hole that registers and aligns with those provided in the concentric plates C and D. The term fabric is used herein in its generic sense and is intended to include cloth, leather, fiber, sheet metal or any similar materials to which it may be desired to attach the cap of the fastener.

Referring in detail to Fig. 7, it will be noted that the backing plate D is provided with slots such as D₁ that register with the longer prongs A₃ of the cap part. This plate is also provided with a central hole D₂ which slips freely over the stud-post E. While the intermediate washer C and the backing plate D serve to reinforce the fabric and properly tie the cap A thereto, it will be evident that these plates C and D do not constitute an essential feature of the socket member of the present invention, since the cap can readily be secured to the fabric by equivalent means.

Referring further to the constructive details of the dished socket cap A of this fastener, it will be seen that its raised side wall A₂ is peculiarly shaped and fashioned into a set of cam elements adapted to engage with the respective legs of the bail-shaped control lever for the purpose of actuating same.

The cap is preferably provided with a double set of cam elements each similar to the one designated as A₈. As is best shown in Figs. 6, 9 and 11, these elements are oppositely disposed with respect to the two journal slots A₅ and A₆ and arranged as duplicate pairs of cam elements. Each such element consists of an undercut recess formed in the raised peripheral side wall A₂ of the cap, which recess extends along the cap edge in the manner indicated in cross-section in Fig. 11. Either pair of such cam recesses are adapted to receive the respective leg portions B₂ and B₃ of the bail lever and co-act therewith in such manner that when the loop of the control lever B is thrown into its mid-position, which is in substantial alignment with the socket axis, the outermost edges of said cam faces will then become engaged with the bail legs and cause the actuated fulcrum tongues B₄ and B₅ to be drawn apart and thus separate the gap between the points thereof.

It will be evident that the resiliency ascribed to the bail-shaped lever at all times holds the legs thereof in close contact with the cam contour. Hence when the bail loop is thrown back into one or the other of its extreme positions to either side of the mid-position, such as is shown in Fig. 4, the bail legs will drop into the undercut cam recess and allow the tongues B₄ and B₅ to spring together into the position shown in Fig. 5.

If, on the other hand, the control lever is again raised into alignment with its socket axis, the relatively large movement given to said lever will only impart a small lateral movement to the actuated bail legs B₂ and B₃. This lateral movement given the bail legs positively open the gap between the tongue ends B₄ and B₅ and this serves to disengage the socket member from its stud-post E.

Referring now to Fig. 1, the described socket member is shown with the control lever thrown out into mid-position, which in turn holds the tongues apart so that the socket may slip freely over the stud-post E, or male member of this fastener. This post is provided with a conical head E₁ which is spaced from the stud proper by an undercut neck portion to form the groove E₂. The projecting portion of this head is rounded off to facilitate the entrance of same into the socket aperture. It will be apparent that the groove E₂ need not be concentric as shown, since an undercut recess of any kind can be made to serve the same purpose.

The essential feature of said post construction lies in the provision for a sharp recessed edge formed behind the head E₁ with which the fulcrum tongues B₄ and B₅ may properly engage. The particular type of stud-post shown in Fig. 1 is provided with a shank E₃ adapted to be driven or screwed into the body portion E₄ of a vehicle or the like to which it is desired to fasten the curtain fabric F.

Figs. 13 and 14 present a modified type of stud-post. The first named figure indicates a stud-post E₅ fastened to a second fabric flap F₁ by means of a suitable reenforcing washer E₆ clinched to the fabric F₁. The socket member may then be secured to an independent fabric F₂ in a manner identical to that previously described in connection with Figs. 1 and 3.

As a further modification in type of stud-post, Fig. 14 shows an elongated double stud E₇ similar to that shown in Fig. 1, except that it is equipt to mount two curtains F₃ and F₄, each provided with independent socket members G₁ and G₂ respectively. The socket G₁ is shown as provided with the cap hole A₄ as in Fig. 9, while in the socket G₂, this hole is avoided by providing the cap crown with a closed hump portion A₁₀ made to clear the projecting stud head E₁ as shown.

Having described the constructive details of this device, the mode of operation of the various parts may be traced as follows:

Figs. 4 and 5 show the relative position of the fastener members after the stud-post E, or male element, has engaged the cap parts, or female element, of this device. It will be noted that the control lever B is now thrown down into one of its extreme or flush posi-

tions which lie substantially normal to the socket axis. From the foregoing description it will be evident that the fulcrum tongues B_4 and B_5 will then drop into the stud groove E_2 and become positively interlocked therewith. The flat faces provided upon each of the tongue ends will be snugly seated behind the undercut groove edge of the stud head E_1 . The resiliency given the control lever B and the fact that the legs thereof are constantly pressing inwardly against the recessed cam element such as A_8 , holds the bail loop in place until such time that it is desired to lift the control lever into its mid or unlatched position.

Should it be desired to maintain said lever in its disengaged position while manipulating the fastener, a shallow notch such as A_9 , as shown in Fig. 6 may be provided, which is intended to register with the respective legs whenever the bail is raised into its mid or unlatched position as shown in Fig. 1.

When the control lever stands in the last named position, the actuated tongue points B_4 and B_5 will be positively held apart by the described cam action and said tongues will be fully disengaged from the stud-post groove E_2 . This action allows the socket member of this curtain fastener to be freely separated from the stud. The projecting bail loop at the same time affords a convenient handle for manipulating the curtain.

It will be apparent that the socket member may readily be removed from, or replaced on, the stud E while the control lever B remains in alignment with the socket axis as shown in Fig. 1. Assuming the stud has been made to enter the socket to the extent as indicated in Fig. 4, the bail lever may thereafter be snapped down into its extreme position and the cam action will then release the forced spacing of the tongues B_4 and B_5 and allow these points to become interlocked with the undercut shoulder of the stud head E_1 . The socket cap member thereby becomes positively locked with respect to the stud and cannot be removed therefrom until the tongue points are again withdrawn from the groove E by manipulating the control lever and throwing same into its mid-position.

The advantage in keeping the control lever B in its mid-position while the stud-post enters the socket member, lies in the absence of all unnecessary resistance between the male and female parts, and this is especially of advantage when two curtains are to be fastened together in the manner indicated in Fig. 13.

On the other hand, if prior to forcing the socket into the engaged position upon the stud-post, it is preferred to throw down the control lever into either of its extreme positions such as is indicated in Fig. 4, the cam elements will then release the spaced fulcrum tongues B_2 and B_3 and allow said

socket to operate in the manner of a snap fastener. A distinction over the conventional snap fastener lies in the fact that said tongues become locked with respect to the stud groove E_2 and that the present invention provides convenient means for positive unlatching the male and female members of this fastener.

It will be seen therefore that the control of the locking and unlocking of the socket member with respect to the stud-post is preferably placed in the resilient bail-shaped lever. When said lever is thrown into either of its extreme positions and flush with the face of the curtain fabric, there will be no projections of any kind and the fastener will present a neat and finished appearance to the eye. Owing to the symmetry of design, the actuating lever may be thrown to either side of its mid-position and held therein until it is desired to remove the socket, and during such time the curtain will remain positively locked to its stud-post.

To unmount the curtain, it is simply necessary to raise the bail loop into its mid or unlatched position when the socket may be freely removed from its stud. It will be apparent therefore that these desirable advantages are attained in an extremely simple manner and that the described fastener is eminently suited to the purpose intended.

The fact that the manipulating handle B is made to stand out normal to the plane of the fabric when it is desired to disengage the fastener, is a feature of special significance as applied to automotive purposes in that the intended purpose of said handle is perfectly obvious to unskilled users and would thus be intuitively operated in its proper manner.

It is not essential to provide for the duplicate tongue and groove locking device as formed by bending the double fulcrum tongues B_4 and B_5 since the use of but one of such locking device can be made to serve the same purpose. It will also be understood that the cap and other socket parts herein disclosed is readily subject to modification in construction, and that various other changes in the details of my device may be resorted to without departing from the spirit and scope of my invention, heretofore described and more particularly set forth in the appended claims.

Claims:

1. In a detachable lock fastener device comprising a male part having a groove, a female member, a control lever for the last named member provided with tongue means adapted to interlock with said groove, and a cam element for actuating said lever adapted to positively disengage said tongue from the groove when the lever is swung about its fulcrum.

2. In a detachable lock fastener device comprising a male part having a groove, a

- female member, a control lever for the last named member provided with a tongue means adapted to interlock with said groove and further provided with a leg member extending from the lever fulcrum, and a cam element adapted to actuate said leg for the purpose of disengaging said tongue from the groove when the lever is swung about its fulcrum.
10. 3. In a detachable lock fastener device comprising a male part having a groove, a female member comprising a socket cap, a resilient bail shaped control lever for the female member provided with tongue means adapted to interlock with said groove, and a pair of cam elements for said cap adapted to actuate the legs of said lever and serving to positively disengage said tongue means from the groove when said lever is swung about its fulcrum.
15. 4. In a detachable lock fastener device comprising a male part having a groove, a female member comprising a socket cap, a resilient bail shaped control lever provided with aligned fulcrum tongues oppositely disposed from the bail legs, means for mounting said fulcrum tongues within said cap and for interlocking said tongues with said groove, and a pair of cam elements adapted
20. to actuate said legs and serving to positively disengage said tongues when said lever is swung about its fulcrum.
25. 5. In a detachable lock fastener device comprising a male part having a groove, a female member comprising a socket cap, a fabric, means for attaching said cap to the fabric, a control lever for the female member, a tongue means adapted to interlock the cap with said groove, and a cam element
30. adapted to actuate said tongue when said lever is swung about its fulcrum and serving to hold said tongue out of engagement when said lever is placed in or near its mid-position.
35. 6. In a combination lock and snap fastener device comprising a male part having a groove, a female member comprising a socket cap, a fabric, means for attaching said cap to the fabric, a control lever for the female member, a resilient tongue means adapted to interlock the cap with said groove, and means for latching said tongue into the groove when the lever is swung into either of its extreme positions and for
40. positively disengaging said tongue from the groove when the lever is placed in an intermediate position.
45. 7. In a detachable lock fastener device comprising a male part having a groove, a female member comprising a socket cap, a fabric, means for attaching said cap to the fabric, a control lever for the female member, a tongue means adapted to positively interlock the cap with said groove,
50. and a cam element adapted to actuate said tongue when said lever is swung about its fulcrum, said element serving to disengage said tongue when the lever is placed in a predetermined position and to latch said tongue into the groove when said lever is moved into another position substantially different from the aforesaid position.
55. 8. In a detachable lock fastener device comprising a male part having a groove, a female member comprising a socket cap, a fabric, means for attaching said cap to the fabric, a control lever for the female member, a resilient tongue means adapted to latch the cap into said groove, and a cam element adapted to actuate said tongue when said lever is swung about its fulcrum, said element serving to hold said tongue out of engagement with the groove when it is desired to separate the male part from the female member and further being adapted to release and latch said tongue into said groove subsequent to remounting the female member upon the male part.
60. 9. In a combined lock and snap fastener device comprising a male part having a groove, a female member, a control lever for the last named member, a resilient tongue means adapted to latch said female member to the male part, and a cam element adapted to actuate said tongue when said lever is swung about its fulcrum, said element being adapted to hold said tongue out of engagement when it is desired to separate the male part from the female member and being further adapted to allow of effective snap action on part of said tongue prior to remounting the female member upon the male part.
65. 10. In a detachable fastener device comprising a male part having a groove, a female member comprising a socket cap of circular contour, a fabric, integral prong means for attaching the cap to the fabric, a journal recess for said cap, substantially aligned with the axis thereof, a control lever provided with a fulcrum tongue mounted in said recess, and a cam element formed in said cap adapted to positively separate said tongue from said groove when lever is swung about its fulcrum.
70. 11. In a detachable fastener device comprising a male part having a groove, a female member comprising a socket cap of circular contour, a control lever provided with a fulcrum tongue mounted in substantial alignment with the axis of said cap, and a cam element formed in said cap adapted to positively withdraw said tongue when the lever is swung about its fulcrum.
75. 12. In a detachable fastener device comprising a male part having a groove, a female member comprising a cap, a curtain fabric, means for attaching said cap to the fabric, a control lever provided with a fulcrum tongue adapted to engage said groove,

means for positively disengaging said tongue when the lever is swung about its fulcrum, and a handle portion for said lever adapted to stand in a substantially 5 normal relation to the fabric face whenever said tongue is disengaged from its groove.

13. In a detachable lock fastener device comprising a male member having a groove, a female member comprising a surrounding 10 socket cap, a control lever for the female member, said lever having a fulcrum whose axis is positioned substantially normal to the axis of the socket part, a tongue means associated with said fulcrum adapted to interlock the male and female members, and a cam element for the cap serving to disengage said tongue means when the lever 15 is swung across the axis of the female member.
14. A socket for a vehicle curtain fastener, having an aperture to receive a grooved stud, and a locking member consisting of a wire loop having its ends journaled into opposite sides of said socket substantially in alignment with the aperture 20 axis and extending inwardly into said aper-

ture to form a tongue means for said groove, the locking member being adapted to be swung about its ends to bring said tongue into locking engagement with said stud 30 groove in either limit of its travel and to disengage the stud in an intermediary position.

15. A socket for a vehicle curtain fastener having an aperture and a recess 35 formed therein, adapted respectively to receive a grooved stud and a wire spring locking member, said member having its fulcrum ends disposed in substantial alignment with said aperture axis and extending inwardly toward the aperture to form a tongue means adapted to engage the stud groove when the locking member is swung into its locking position and to disengage said tongue when said member is moved into 40 its unlocking position.

In testimony whereof I have herewith set my hand this 28th day of November, 1923.

DANIEL M. WINANS.
